ABSTRACT

A thin-wall hollow push rod has in it a co-axial tube of small bore running from end to end through the hollow interior thereof. The bore of the tube is sufficiently large to permit a controlled stream of oil under pressure to flow therethrough, and sufficiently small as to prevent churning of the oil which produces a foam having bubbles in the oil stream. This hinders return of oil to the crank case. Ball surface bearings with bores therethrough are affixed at each end of the tube, and the ends of the tube are disposed in counterbores in the ball surface bearings.

BALL ENDED PUSH ROD WITH CONTROLLED OIL FLOW

RELATED APPLICATION

Hayward, PUSH ROD WITH CONTROLLED OIL FLOW, Serial No. 394,805 filed September 6, 1973, of which this application is a continuation in part.

FIELD OF INVENTION

Internal Combustion Engines, Poppett Valve Operating Mechanism, Rod.

PRIOR ART

Almen U.S. Pat. No. 1,823,419; Mannerstedt U.S. Pat. No. 2,878,796.

OBJECTS

Hollow push rods for actuating valves of internal combustion engines have been known for many years, a typical example of which is shown in FIG. 3 of the Almen patent (supra). These thin-wall rods are usually open at the ends to permit oil to pass therethrough. Not only does the oil add to the inertia of the usual hollow rod, but also, due to the rapid reciprocation of the rod in high-speed engines, the oil churns back and forth so much that air bubbles in the oil stream are produced, and these air bubbles make it difficult to return the oil to the crank case. One solution to the bubble problem might appear to be the use of a solid push rod with a smaller oil passage therethrough, such as the one shown in Mannerstedt (supra). However, solid rods are heavier and, if they are made with the same amount of metal as a hollow rod, they are not so strong. Another solution, which has been attempted by racing car mechanics, is to insert pipe cleaners into the hollow interiors of push rods. These reduce churning, but there remains the weight of the oil which fills the rods, with resultant inertia, the oil flow through the rod is impeded, and there is a resultant danger of foreign substances from the pipe cleaners getting into the oil stream. Also, the twisted metal rod of the pipe cleaner may enter the hole at the end of the rod and clog it up. My object is to produce a push rod for valves which conducts oil from end-to-end, which is almost as light as the ordinary hollow rod, which is as strong or stronger than the ordinary hollow rod, but in which the oil cannot churn so as to produce air bubbles in the oil stream. To this end, it is intended now to provide a thin-wall hollow push rod having a relatively small hollow tube running coaxially therethrough from end to end controlling the flow of oil therethrough. More specifically, it is preferred that the bore of this tube be capillary in nature.

Application Ser. No. 394,805 discloses a hollow push rod with hollow ends having holes therethrough sufficiently large to accommodate the ends of a capillary tube which extends coaxially therethrough from end-to-end. However, some makes of automobiles use hollow push rods with ball surface bearings welded into the ends, the ball surface bearing having bores across them through which oil flows. It is to this type of push rod to which the present invention is addressed.

It is the object of this invention to provide a hollow push rod having ball surface bearings secured in the ends thereof, each bearing being solid but for a bore which extends therethrough, wherein the bores having counterbores in the ends thereof which face the interior of the hollow push rod. A small hollow tube, pref-

erably having capillary characteristics as regards lubricating oil, e.g., a thin-wall tube having a bore of about one-sixth inch diameter, has its ends engaged in the counterbores of the bearings. This not only provides a finished surface for the bearings, unbroken save for the bore ends, but, perhaps more importantly, a great manufacturing advantage in assembling. Because the ends of the tube engage closely into the counterbores in the bearings, the rod can be assembled by engaging one end of the tube into the counterbore of a first bearing, then the free end of the tube is inserted end-wise through the hollow rod until the first bearing engages into an end of the hollow rod, then the counterbore of the second bearing is engaged over the free end of the tube and, with the bearings engaged into the respective ends of the hollow rod, the bearings are welded into place. Alternatively, an end of the tube can be welded into the bore of the first bearing before the free end of the tube is inserted through the hollow rod. However, this preliminary welding step is not absolutely necessary because, once the bearing balls are welded into place, the tube is locked into place, and, furthermore, if the bearings are affixed into the ends of the hollow rod by inductive welding, the ends of the tube can be simultaneously welded to the bearing balls.

These and other objects will be apparent from the following specification and drawing, in which:

FIG. 1 is a perspective view of the push rod in typical environment of use; and,

FIG. 2 is an exploded view of the parts of the push rod.

Referring now to the drawings, in which like reference numerals denote similar elements, the hollow push rod 2 is formed of a hollow rod 4 whose inner edges 6 are beveled at both ends for receiving bearings which in this example are balls 8 and 10 which are welded as at 11 to the beveled edges. The bearings balls 8 and 10 engage against concave seats 12 and 14 in a valve lifter 16 and a rocker arm 18, respectively. Oil under pressure is supplied via a cross passage 20 and longitudinal bore 22 in the lifter, thus oil flowing through bores 22 in the bearing ball, through the hollow push rod and to an oil hole 24 in the rocker arm. As thus far described, the hollow push rod is conventional for certain makes of automobiles and in a typical example the push rod would be about 6 $\frac{3}{4}$ inches long, about 5/16 inches outer diameter and about 13/64 inches inner diameter. These dimensions, of course, change in accordance with engine specifications. The valve lifter and rocker arm form no part of the invention and may partake of various forms so long as some sort of mating pressure oil supply is provided for one end of the rod, and some sort of mating oil receiving means is provided for the other end of the rod. The problem solved by this invention is that ordinarily oil fills the interior of the hollow rod and, because of rapid reciprocation, churns and form bubbles which are harmful to the lubricating system of an engine, and extremely difficult to get rid of.

According to this invention, each ball is provided, in addition to the transverse bore 26, a counterbore 28, and tightly engaging in the counterbores 28 are the ends of a thin wall tube 30. Although dimensions may change from model to model, in the example being described, the outer diameter of tube 30 is about 3/32 inches, the wall 32 is about 1/64 inch, and the axial bore 34 is about 1/16 inch. The counterbore 28 in bear-

ing balls 8 should be, in this case, about 3/32 inches in diameter to provide a tight fit over the ends of tube 30.

In assembling rod 2, one end of tube 30 is inserted into the counterbore 28 of one bearing ball, such as ball 8, the then free end of tube 30 is inserted through hollow rod 4, the counterbore 28 of other bearing ball 10 is fitted over the free end of tube 30 so that both bearing balls are firmly seated against the beveled end edges 6 of hollow rod 4, and then both bearing balls are joined to the rod ends by welds 11. With some welding processes, such as inductive welding, the ends of the tube 30 can be simultaneously welded in place. Otherwise, if needed to provide a leak-proof joint between the ends of the tube 30 and the bearing balls a sealing compound may be used, it being preferred that no oil enter the hollow space 36 between the tube 30 and the inner wall of hollow rod 4, because this would add to the weight of the rod.

The diameter requisite for the bore 34 of tube 30 is that it be sufficiently small that lubricating oil, a somewhat viscous liquid, will not churn enough to form bubbles. It is preferred that the bore of the tube be capillary in nature so that lubricating oil will adhere to its sides and thereby tend to reciprocate with the tube, rather than undergo cavitation with resultant entrainment of air. In some hollow push rods, the ball surface bearings are not entirely spherical but, rather, are somewhat bullet-shape, with substantially hemispherical bearing surfaces at the exposed ends.

I claim:

1. A push rod for actuating a poppet valve of an engine and for transmitting oil, comprising an elongate hollow tube having abutment means at opposite ends thereof, and means providing a capillary passage from end-to-end through said tube and said abutment means, the means providing a capillary passage comprising a second tube whose outer diameter is substantially less than the inner diameter of the first-mentioned tube, and means securing the opposite ends of the second tube in said abutment means, the space between said diameters being hollow.

2. A push rod as defined in claim 1, said abutment means comprising bearing members respectively secured in opposite ends of said hollow tube, said bearing members each having bore means extending therethrough in the axial direction of the tube, and each having an inner end portion open towards the interior of the tube and an outer end portion open oppositely therefrom, the ends of said second tube being respectively secured in the inner end portion of the bore means in the bearing members.

3. A push rod as defined in claim 2, the outer end portions of the bore means having a diameter substantially equal to the inner diameter of the second tube and the inner end portions of the bore means having a diameter but slightly larger than the outer diameter of the second tube whereby the ends of said second tube engage snugly in the inner end portions of the bore means.

4. A push rod as defined in claim 2, said bearing members being spherical.

5. A push rod for actuating a poppet valve of an engine and for transmitting oil, comprising an elongate hollow tube having abutment means at opposite ends thereof, and means providing a passage from end-to-end through said tube and abutment means,

the means providing a passage comprising a second tube whose outer diameter is less than the inner diameter of the first-mentioned tube, and means securing opposite ends of the second tube in said abutment means, the space between said diameters being hollow.

6. A push rod as defined in claim 5, said abutment means comprising bearing members respectively secured in opposite ends of said hollow tube, said bearing members each having a bore therethrough, the ends of said second tube being respectively secured in the bores of the bearing members.

7. A push rod as defined in claim 6, said bearing members being spherical.
